UNITED STATES PATENT OFFICE.

HANNAH T. FARMER, OF NEWPORT, RHODE ISLAND.

HEAD-PROTECTOR.

SPECIFICATION forming part of Letters Patent No. 290,017, dated December 11, 1883.

Application filed March 1, 1881. (No model.)

To all whom it may concern:

Be it known that I, HANNAH T. FARMER, a citizen of the United States, residing at Newport, in the county of Newport and State of Rhode Island, have invented certain new and useful Improvements in Pads for Protecting the Head from Heat, of which the following is a specification.

I am aware that heretofore leaves, wet cloths, sponges, and pads have been worn within the hat to protect the head from the rays of the sun. My invention, however, consists in an improved construction of a pad to be worn within the hat, possessing certain advantages over those heretofore in use.

In the accompanying drawings, Figure 1 is a view of my improved pad, and Fig. 2 shows a central section of a hat containing the pad in place above the head of the wearer.

The pad A is composed of sponge cut or torn into small particles and inclosed in a case or bag, B, of netting, and stitched or quilted in a manner well understood and illustrated in the figures. When the sponge is wetted, it is

prevented from unduly swelling or changing its shape by its quilted cover. It will therefore readily remain in place and conform to the shape of the head, and will at the same time hold in suspension a sufficient quantity

of water or other liquid with which it may be moistened. As the cover is constructed of netting, the pad is very light, and therefore not cumbersome to the head of the wearer. This has been an objection to pads heretofore

in use, as well as to the cloths which have also been used. These would not absorb a sufficient quantity of water to keep the head cool and moist, while ordinary sponges, if large enough to cover the top of the head, were too

bulky, and, if wetted enough to keep the head properly moist and cool, were too heavy. They were also, on account of their size and

shape, liable to wet the hat and injure its shape. Small sponges would also get out of place and roll against the sides of the hat. 45

My pad, being constructed of fragmentary sponge inclosed in and firmly stitched to the netting-cover, requires a comparatively-small quantity of sponge, which, with the cover of netting, constitutes a light and durable pad, 50 obviating all the objections referred to.

If desired, the pad may be secured to the lining of the hat by a device which permits it to be readily detached and removed when not needed. I have shown, for this purpose, two short pieces of elastic tape, D D, which are provided with metallic hooks d d. Similar tapes, E E, provided with corresponding eyes, e e, are sewed at two opposite points upon the periphery of the pad. By clasping the hooks 60 and eyes in the usual manner the pad is effectually secured in place.

The pad may be used for horses or other animals with advantage, the mode of attachment to the head-gear of the harness being 65 obvious without detailed explanation.

I do not broadly claim herein, as a means of protecting the head from heat, a pad composed of absorbent material to be worn within the hat, as I am aware that such head-protectors are old and well known. 70

I claim as my invention—

In a head-protecting pad, the combination of the fragmentary sponge and the netting-cover inclosing the same, the sponge and cover 75 being stitched together or quilted, as set forth.

In testimony whereof I have hereunto subscribed my name this 1st day of January, A. D. 1881.

HANNAH T. FARMER.
